UNITED STATES PATENT OFFICE.

YVES PAUL GASTON LE PRIEUR, OF PARIS, FRANCE, ASSIGNOR TO SOCIÉTÉ ANONYME
LA PRÉCISION MODERNE, OF PARIS, FRANCE.

APPARATUS FOR EFFECTING GUNNERY CALCULATIONS.

Application filed August 31, 1922. Serial No. 585,569.

To all whom it may concern:

Be it known that I, YVES PAUL GASTON LE PRIEUR, citizen of the French Republic, residing at 61 Rue Pernety, Paris, France, 5 have invented certain new and useful Apparatus for Effecting Gunnery Calculations, of which the following is a specification.

The problem of gun laying on board a 10 vessel consists in furnishing to the pieces of artillery the elevation and the lateral allowance at each instant, these being essentially variable, which are required in order to place the projectiles upon the target. The 15 values of the same will depend upon the following factors; the course and speed of the firing vessel, the course and speed of the target vessel, and the direction and force of the wind. The effect of these factors will be 20 distributed upon the elevation and the lateral allowance according to the bearing of the target with reference to the firer i. e., the angle of the target counting from the front of the firer. For determining these 25 factors, account is to be taken of certain corrections, especially the drift of the projectile due to the rifling of the gun.

Considering the firing plane, as defined 30 by the firer and the target, the components according to this plan of the forces due to the said elements will give rise to corrections in the range, according to which the gun should be set in elevation, said corrections depending upon the distance and being furnished by the firing tables; these 35 corrections are to be algebraically added to form the total correction which is added to the actual distance from the firer to the target which will give the modified range 40 which is to be employed when elevating the gun. In like manner, the components, perpendicular to the firing plane, of the forces due to the said factors will have an effect upon the lateral allowance. By algebraically 45 adding the resulting corrections and also adding the drift proper of the projectile, the total lateral allowance to be employed will be obtained.

As a rule, the firing officer measures or 50 estimates the value of the above-mentioned factors and then determines the desired corrections for elevation and lateral allowance by the aid of the firing tables; he also adds together the range corrections and adds 55 their total to the actual distance from the

target in order to obtain the modified range, then adds the corrections for the lateral allowance and adds to the same the drift whereby he will obtain the total lateral allowance. But the use of the firing tables is 60 a source of frequent errors and especially requires a certain time, so that instructions for the modified range and lateral allowance, which vary rapidly in some cases, will be subject to delay when communicated to 65 the pieces.

When the firing has been commenced with the modified range and lateral allowance as thus found, an observation of the points of fall of the projectiles with reference to the 70 target will often bring out errors for whose correction the firing officer is led to make adjustments in the modified range and lateral allowance whereof he determines the value in each case.

The modified range and the lateral allowance, and especially the former, are subject to continual variations. Known devices are employed for automatically following the variations of modified range when one has 80 determined the speed of approach of the firer and target and when one regulates or operates said devices in consequence. But said devices are not absolutely exact, as they occasion loss of time or fail to take account in an absolutely continuous manner 85 of the rapid variations in the firing factors.

The present invention relates to a device which obviates all these drawbacks and shows in an automatic and instantaneous 90 manner upon suitable dials the modified range and the lateral allowance to be used, after having set upon various other dials the estimated or measured values of the factors affecting the firing, i. e., course and speed 95 of the firer, course and speed of the target and force and direction of the wind. The said apparatus also provides for making adjustments in modified range and lateral allowance when required.

The principle of the said apparatus is as follows: Three dials mounted on a common centre line are each provided with a graduated pointer which carries a cursor or slide; said dials correspond to the firing vessel, the 105 wind and the target vessel. The arms are oriented and the slides are placed so the setting of the cursors or slides relatively to the pointers can be provided in any known way, by example each pointer will carry a 110

threaded rod and the cursor or slide, which is internally threaded, will be displaced on the said rod along a graduation carried by the pointer.

- 5 The pointers are oriented to correspond with the direction of the speed of the firer, of the speed of the wind and of the speed of the target, and the cursors are set upon said pointers in such a manner that the distances of said cursors from the axes of the pointers represent these speeds in magnitude but are of opposite sign to them.

The centre line represents the firing plane. The apparatus contains carriages which are actuated by the said cursors or slides certain of the said carriages being movable in a direction parallel and others perpendicular to the firing plane and these will show by their displacement the value of the components of these three speeds measured in the direction of the firing plane and at right angles thereto. The displacements of said carriages, when combined with the action of cams which are formed in accordance with the firing tables and are turned or set according to the distance from firer to target, will cause the movement of other carriages, whereof a certain number move parallel and others perpendicular to the firing plane, and will impart to said carriages various displacements which represent the corrections for modified range and lateral allowance which are due to each factor. The total sum of the components (according to the firing plane) of the speeds of the firer and of the target will give the speed of approach which is indicated upon a dial; a speed-indicator which is disposed on the same axis as the pointer of said dial is operated by hand so as to maintain coincidence between the pointer and that of the dial, i. e., so as to rotate at a speed corresponding to the speed of approach. The mechanism of said speed-indicator also actuates one of the gear wheels of a double differential which carries the pointer indicating the modified range, and therefore if the latter indicates the proper modified range at any given moment, it will continually follow the variations of distance due to the speed of approach. The totalizing (by mechanical means) of the corrections arising from the three components according to the firing plane will afford the total correction for the modified range, and this is transmitted to a second gear wheel of the double differential carrying the pointer indicating the modified range. Adjustments in the modified range will be made by acting upon another pinion of this double differential. In like manner the totalizing (by mechanical means) of the corrections for lateral allowance depending upon the three components perpendicular to the firing plane will be transmitted to one of the wheels of a differential

whereupon is mounted the lateral allowance pointer. To this is added the drift of the projectile proper, by causing a cam formed by the use of the drift table and set according to the distance to act upon the second wheel of the differential. Adjustments in the lateral allowance are made by the angular displacement of the dial used with the lateral allowance needle.

A form of construction of the apparatus is set forth by way of example in the following description together with the accompanying drawings.

Fig. 1 is a general plan view of the top of the apparatus and of certain interior elements, and Fig. 2 a like view with the top cover removed showing the interior elements. Figs. 3 and 4 show on a larger scale the devices giving corrections for modified range and lateral allowance resulting from one of the said factors, speed of the firer, of the wind and of the target. Fig. 5 shows on a larger scale and rotated through 90° the left hand part of Fig. 2, and adjacent the plan views are also shown various parts such as in Fig. 6 the speed-indicator and its mechanism in elevation; in Fig. 7 the double differential actuating the pointer for elevation value and its mechanism; in Fig. 8 a diagrammatic section of the double differential; in Fig. 9 the differential actuating the lateral allowance pointer and its mechanism; and in Fig. 10 a diagrammatic section of said differential.

Along the central line 18 of the box 1, Fig. 1, are disposed three dials 2, 3, 4 corresponding respectively to the firing vessel, the wind and the target vessel.

The dials 2, 3, 4 are rotatably mounted respectively upon orienting dials 11, 12, 13 which are connected together, as hereinafter explained, so as to be always oriented alike. Upon the dials 2, 3, 4 are rigidly mounted pointers 5, 6, 7 respectively, and along the said pointers may be respectively displaced cursors or slides 8, 9, 10; the pointers are oriented relative to the dials 11, 12, 13 and the cursors set in such a manner that the vector distances from the axes of the pointers to the cursors correspond in direction and magnitude according to the chosen scale, to the speed of the firer, the absolute speed of the wind and the speed of the target, but are of opposite sign to them. The dials 11, 12, 13 are graduated in degrees and are marked to correspond with the points of the compass, north, south, east, west. These dials 11, 12, 13 are to be oriented in such a manner that the north to south line on the orienting dials occupies with reference to the central line 18, the same relative position as the actual north and south line occupies in space with reference to the actual plane of firing. For this object it is necessary to impart to the dials 11, 12, 13

an angular displacement equal to the algebraic sum of the bearing of the target with reference to the firing vessel, and of the course of the firing vessel.

- 5 For this purpose a hand crank 14 placed beside the dial 2 of the firing vessel drives a gear wheel 15 mounted on shaft 16 which carries the worm gear engaging the dial of the firing vessel 2; said crank 14 orients the 10 pointer 5 representing the firing vessel so that this pointer 5 will make with the firing plane 18 represented by the centre line common to the three dials 2, 3, 4 an angle equal in magnitude but of opposite sign 15 to the bearing of the target relative to the firing vessel. The gear wheel 15 is engaged with the gear wheel 19 of a differential 20 whereof the other wheel 21 is driven by a worm 22 mounted on a shaft 23 20 whereof the handle 24 is operated by hand according to the bearing of the firing vessel. The shaft 25 of the planetary gears of differential 20 carries three worm wheels 26, 27, 28 respectively engaging the orienting 25 dials 11, 12, 13. The rotation of the shaft 25 is equal to half the algebraic sum of the rotations of the wheels 19 and 21, and consequently corresponds to the algebraic sum 30 of the course of the firing vessel and of the bearing of the target relative to the firing vessel. This shaft 25 will thus correctly set the orienting dials 11, 12, 13 in the direction hereinbefore stated.
- The setting of the wind pointer 6 on its 35 dial 12 is effected by crank 29 actuating gear wheel 30 pertaining to a differential 31 whose other gear wheel 32 engages a wheel 33 keyed to the shaft of orientation 25 of the orienting dials. In this manner the 40 shaft 34 of the planetary gears of the differential 31 (similar to differential 20) which is provided with a worm wheel 35 engaging the wind dial 3 will give to said dial and hence to wind pointer 6 secured thereto a correct orientation with respect to its orienting dial 12. In like manner the setting of the target pointer 7 on its orienting dial 13 is effected by crank 36 engaging a gear wheel 37 of a like differential 38 whereof the other 45 gear wheel 39 engages a wheel 40 on the orientation shaft 25 of the horizon dials. In this manner, the shaft 41 of the planetary gears of differential 38 provided with a driving worm 42 engaging the target dial 4 will place the target pointer 7 in the correct orientation with respect to its dial 13.

By means of said devices and the operation as indicated, the firing combination apparatus will afford a correct representation, with respect to the orienting dials, of the orientation and the speeds of the firer, the target and the wind, as well as of the firing plane.

The determination of the components of each of the speeds i. e., those of firer, wind

and target is effected by devices of identical nature whereof only one need be described, for example the one used for the speed of the firer, said devices being shown in Figs. 2, 3 and 4.

70

Below the firing dial 2 and its orienting dial 11 is mounted a carriage formed by a plate 43 (Figs. 2 and 3) having the slot 44, perpendicular to the firing plane, and which can only be moved parallel to the firing 75 plane. Below said plate is a second carriage formed by a plate 45 (Figs. 2 and 4) having the slot 46 parallel to the firing plane, and which can only be moved perpendicular to the firing plane. As previously explained 80 the cursor 8 is mounted upon the firing pointer 5 which has been properly oriented in such a manner as to make with the line 18 the same angle as the course of the firing vessel makes with the plane of firing. The cursor 8 is set at a distance from the axis 85 of rotation of the pointer 5 representing on the chosen scale the magnitude of the speed of the firer, but being of contrary sign thereto. The cursor 8 is provided with a 90 vertical stud which is engaged both in slots 44 and 46. In this manner, the plates 43, 45 will at each instant have received—with reference to their zero position corresponding to the setting of the cursor 8 at the 95 centre of its dial—a displacement according to the firing plane and perpendicular to said plane which will measure the components (according to these two directions) of the speed of the firing vessel.

100

To ascertain from the components of the speeds of the firer and of the target according to the plane of firing, the speed of approach of the two vessels, the following mechanism has been devised. The upper carriage of the firer, Fig. 2, carries the pulley 47 and the corresponding carriage of the target carries the pulley 48; upon said pulleys is mounted the cable 49 having one end fixed at 50. Said pulleys have movements parallel to the firing plane which correspond to components (in this plane) of the speed of the firer and the speed of the target, and therefore the outer end of the cable 49 will move by a quantity equal to the algebraic 105 sum of these two components; said outer end is wound upon a drum 51, Fig. 6, which is secured to a pointer 54 moving on a dial 53 graduated in speed of approach. The speed of approach thus found will be used 110 to vary the modified range in a continuous and corresponding manner by means of the following devices.

115

The dial 53 pertains to a speed-indicator whose pointer 52 is mounted on a copper bell 52' actuated at a distance by a magnet 53' mounted on a flywheel 53''. The speed-indicator is actuated by a shaft 55, Fig. 5, provided with a hand crank 56, by means of a loose gear wheel 57 adapted to be coupled 125 130

to the shaft 55 by a jaw clutch 58 controlled by the handle 58', Fig. 2, and rods 59', 59'', said clutch being normally engaged. The shaft 55 ends in a worm 59 which is in gear 5 with a wheel 84 which through a suitable transmission operates the pointer 60. By example the wheel 84 is fixed to a pinion 151. The pinion 151 is in gear with the pinion 152 fixed upon the shaft 153 which 10 carries also the pinion 154 which is in gear with the pinion 155 to which the pointer 60 is fixed. The pinion 60 indicates the hundreds of metres of the actual distance on the range dial 61. Said dial is also provided 15 with a pointer 62 for kilometres of distance which is connected with the former by suitable gearing. The handle 56 is operated so as to maintain the pointer 52 of the speed indicator in con ordance with the pointer 54 20 and this will rotate the speed-indicator at a speed corresponding to this speed of approach. One will thus vary the indication for the distance by amounts corresponding to said speed of approach. The apparatus 25 is regulated so that the distance will vary on the dial, in a given time, by the amount of variation in the true distance between firer and target.

Concerning the mechanism for totalizing 30 the corrections for modified range and the addition of the same to the distance, the modified range is given as follows, Fig. 3. Each of the three carriages 43 (for instance that of the firer) carries a button 63 engaging a 35 slotted arm 64 pivoted at a fixed point 65. Below said arm is the carriage 66 having a slot 67 perpendicular to the firing plane and movable only parallel to said plane; below said carriage is a second carriage 68, 40 Fig. 4 which can move only perpendicular to the firing plane and is provided with a guide parallel to the firing plane wherein is movable a flat bar 69 provided with a vertical stud 70 engaged in the slot 67 of carriage 66 and in the slot of the arm 64. The 45 position of the carriage 68 in its movements perpendicular to the firing plane is regulated by a cam 71 pivoted at 72 and actuating a roller 73 disposed on carriage 68. The 50 cam 71 is secured to a worm wheel 73', Fig. 2, engaging a worm 74 mounted on a shaft 75 which is driven by the shaft 55 (used for the distances) through the medium of a gear wheel 76 and a worm 76' disposed on shaft 55. The cam 71 is given an outline according to the firing table which gives the correction for modified range due to the component of the speed of the firer in the firing plane. Said correction depends upon 55 the actual distance and said component of speed. Cam 71 may be so formed that the value of the movements (parallel to the plane of firing) of a pulley 77, Fig. 3, mounted on carriage 66, shall represent this 60 correction at the chosen scale. In like manner, the corrections for modified range due to the wind and to the target will be measured by the displacements of pulleys 78, 79, Fig. 2, mounted on carriages analogous to chariot 66 and actuated in like manner. 70 The totalization of these three corrections is carried out by means of a cable 80 whereof one end is secured at 81 and which is disposed upon the three pulleys 77, 78, 79, and whereof the other end is wound upon 75 the gear wheel 82 of a differential 83 Fig. 7, whereof the other gear wheel is driven by the shaft for the distances 55, and whose secondary shaft 83' Fig. 8, carrying the planetary gears is secured to the lower gear 80 wheel 83'' of a second differential 83a. The 85 adjustments for modified range can be obtained by a crank 85 Fig. 2, driving a shaft 85' ending in a worm 86 which engages the upper wheel 86' of this second differential Fig. 7, whereof the secondary shaft of the planetary gears carries the pointer 60' indicating the modified range. The shaft 85' also actuates a pointer 87, Fig. 2, moving on a dial 88 whereon are shown in the desired 90 sense the modified range adjustments produced, thus affording a check upon the same.

The mechanism for totalizing the corrections for the lateral allowance is as follows. For each of the three dials, that of the 95 firer, for example, the carriage 45, Fig. 2, is given (as stated) a displacement perpendicular to the firing plane which measures the component of the speed of the firer according to this direction. It is now proposed to bring this displacement parallel to the firing plane so as to obtain a certain symmetry in the apparatus concerning the three dials for firing, wind and target in effecting to some extent a correspondence 100 between the elements used for totalizing the corrections value and those used for totalizing the corrections for lateral allowance. To this end the carriage 45, Fig. 4, is provided with a button 89 actuating the arm 105 90 of a bell-crank lever pivoted at the fixed point 91 and whereof the other arm 92 is provided with a slot 93. Below said lever is a carriage 94 having slot 95 perpendicular 110 to the firing plane and movable only parallel to the firing plane. Below said carriage 94 is disposed, Fig. 3, a second carriage 96 movable only perpendicular to the firing plane and provided with a guide 97 parallel to the firing plane wherein is slideable a flat 115 bar 98 provided with a vertical stud 99 engaging both in the slot 95 of carriage 94 and in the slot of the arm 92. The carriage 96 carries a roller 100 which is constantly pressed by a spring upon a cam 101 pivoting 120 on the axle 102. Said cam has a profile which is determined according to the table of corrections for lateral allowance corresponding to the component of the speed of the firer perpendicular to the firing plane. 125 130

This correction depends upon the said component and the distance. The cam 101 may be so shaped and actuated that the movement of carriage 94 parallel to the firing plane will represent the said correction on the chosen scale. Cam 101 is secured to a wheel 103, Fig. 2, actuated by a worm 104 mounted on a shaft 105 driven from the distance shaft 55 by means of the gear wheel 106 and the worm 106' mounted on shaft 55. The carriage 94 carries a pulley 107; in like manner the pulleys 108, 109 are disposed upon carriages similar to 94 corresponding to the wind and to the target. A cable 110 whereof one end is secured at 111 is disposed on the three pulleys 107, 108, 109 and is wound at the end on one of the pinions 110' Fig. 9, of a differential 112 whose secondary shaft 113 carries the lateral allowance pointer 114 moving on the dial 115. The second gear wheel 116 of said differential is actuated by a rack 125 controlled by a cam 126 which is formed according to the table of corrections for drift 25 of the projectile due to the rifling which depend upon the distance of the firer from the target; cam 126 is secured to a worm wheel 127 actuated by the worm 104' on shaft 105. The dial 115 is actuated by the worm 117 mounted on a shaft 118 hand-controlled by the crank 119, Fig. 2, and serving to obtain the adjustments in lateral allowance, these being shown with their sign (to the right or left) on a dial 120 30 whose pointer 121 is also actuated by the shaft 118 by means of a worm 118'. It is necessary that the control shaft 55 for the distance pointer shall be disengaged at will from the speed-indicator which it 40 drives, so that the distance may be rapidly varied either at the commencement of the firing or upon changing the target, or again, in the event of a considerable error, and to this end the jaw clutch 58 of the loose driving wheel 57 can be disengaged by means of the handle 58'.

In certain cases it may be advantageous to use as the basis of the firing corrections not the true speed or true direction of the 50 wind, but the apparent speed and direction of the wind with respect to the firing vessel. To facilitate in this case the movement of the wind pointer 6, Fig. 1, there is disposed below the orienting dial thereof a second 55 dial 122 having a checking arrow pointer 123 used for reproducing the bearing of the firing vessel and which is brought parallel thereto by means of gearing 124, 124' which is actuated by the firing dial 2 and drives 60 the dial 122. After measuring the apparent speed and direction of the wind, it is simply necessary in order to orient the wind pointer 6 to operate the crank 29 so that the wind pointer 6 shall have a measured angle with 65 the arrow pointer 123.

The speed-indicator will only operate in a regular manner when the hand control of the same is neither too fast nor too slow. The crank 56 is used for the high speeds of approach; for small speeds, use is made of another crank 56', Figs. 2 and 6, actuating the flywheel of the speed-counter by an endless belt 56'' formed by an endless coiled wire spring, the said drive having a speed-increase ratio which is smaller than the preceding and is adapted to slip, so that the flywheel of the speed-counter, which moves by its own inertia will have a more regular movement than if it were rigidly connected with its hand control means. 80

The firing officer is required to have before him the distance from firer to target, and the totals of the corrections for modified range and lateral allowance resulting from the three elements, firer, wind and target. 85 As stated, the actual distance is shown by two pointers 60, 62 whereof one corresponds to hundreds of meters and the other to kilometers, this second pointer being controlled by the first by means of suitable gearing.

The total of the three corrections for modified range is shown by a pointer 129, Fig. 2, actuated by the gear wheel or drum 82 upon which the three corrections are 90 totalized.

The total of the three corrections for lateral allowance is shown by a pointer 130, Fig. 2, actuated through a suitable gearing (see Fig. 2) by the gear wheel or drum 110' 100 upon which these three corrections are totalized. It must be remarked that the pointer 130 gives only the corrections arising from course of firer, course of target and wind, and that the drift correction is not 105 added to the said three corrections, whereas same is comprised in total given by pointer 114.

What I claim is:

Apparatus for effecting gunnery calculations comprising three pivoted pointers, whose axes are situated upon a common straight line, a cursor upon each pointer, means for orienting said pointers and for setting the said cursors in such a manner that 110 the distances of the cursors from the axes of rotation of the pointers correspond in magnitude, but are of contrary sign to the vectors representing the speed of firer, speed of wind and speed of a target, while the 115 line of the axes corresponds to the firing plane; means for obtaining the components of said vectors in the direction of the firing plane and in a plane perpendicular to the same; a totalizing device for the components 120 in the firing plane of the speed of the firer and speed of target, said device comprising a pointer indicating the speed of approach; a speed-indicator and means for actuating the same at the said speed of approach, 125 130

- means for indicating the value which varies with the distance of the three corrections for modified range due to the components—parallel to the firing plane of the 5 three speeds of firer, wind and target; a totalizing device for these three corrections; a double differential carrying the pointer for the modified range and totalizing upon the same the movements which it receives from the means actuating the speed-indicator, from the device for totalizing the 10 three corrections for modified range and from the actuating shaft for effecting adjustments in the modified range; means for indicating the total value which varies with the distance of the three lateral allowance 15 corrections due to the components perpendicular to the firing plane of the three speeds of firer, wind and target; a differential carrying the pointer for lateral allowance and totalizing upon said pointer the movements which it receives from the device totalizing the three corrections for lateral allowance and from a cam actuated by the means actuating the speed indicator 20 and indicating the drift; and a device for rotating the dial, on which reads the pointer indicating the lateral allowance, in such a manner as to effect adjustments in lateral allowance. 25
- 30

In witness whereof I have hereunto set my hand.

YVES PAUL GASTON LE PRIEUR.
